PERCUSSION TOOL

Rudolph Goldschmidt, Sheffield, England

Application February 16, 1944, Serial No. 522,681
In Great Britain March 5, 1943

14 Claims. (Cl. 125—33)

1

This invention relates to mechanically-operated percussion tools, such for example as power hammers, riveters and paving-breakers.

An object of this invention is to provide a percussion tool which is relatively light and compact and which is economical in power consumption.

A further object is to provide such a tool which can be readily designed to give blows of any desired frequency and energy.

Another object is to provide an electrically-operated tool having the above-mentioned advantages.

Another object is to enable a percussion tool to be operated by a high-speed rotary motor without reduction gearing.

Another object is to enable a percussion tool, such as a riveter, which is intended for intermittent use, to store during an idle period kinetic energy which is usefully employed during the subsequent working period.

Further objects and features of the invention will be apparent from the following description of an example thereof as applied to a hand tool and given with reference to the accompanying diagrammatic drawings, in which:

Fig. 1 is a longitudinal section through the tool,
Fig. 2 is a section on the line 2—2 in Fig. 1,

Fig. 3 is an elevation of a detail, as viewed in the plane of Fig. 1.

Figs. 4 and 5 show respectively two alternative forms of this detail,

Fig. 6 is a section on the line 6—6 in Fig. 1,
Fig. 7 is an explanatory diagram,

Fig. 8 is a section on the line 8—8 in Fig. 1,
Figs. 9, 10 and 11 are respectively sections on the lines 9—9, 10—10 and 11—11 in Fig. 8,

Fig. 12 is an explanatory diagram, and
Fig. 13 is a section on the line 13—13 in Fig. 12.

Referring to Figs. 1, 2 and 3, the tool includes a tubular body 20, an electric motor 21 fixed to a flange 22 at the outer end of the body, and a tool-bit holder 23 slidably guided in an inner end cap 24 of the body for limited movement along the axis of the motor shaft 25. A striker includes a flywheel 26 which is slidably engaged with a splined extension 25A of the motor shaft. An extension 27 of the tool-bit holder 23 is provided with a journal 28 slidably fitted in a bore 29 in the lower end of the shaft 25A in such a manner as to permit the longitudinal movement of the tool-bit holder. In the periphery of the striker are two diametrically-opposed pockets 30 each accommodating a hardened steel roller 31 which has two co-axial pins 32 guided in radial slots 33 in the striker; the roller is thus constrained to

2

be carried round and move longitudinally with the striker, but is free to move radially with respect to the striker under the influence of centrifugal force, while its axis is kept parallel to that of the motor shaft by the restraint afforded by the surfaces of the pockets in which the grooves 33 are formed. The extent of the radial movement of the rollers is determined by the inner surface of the body, on which circumferentially ridged portions 34 of them bear continuously while the tool is operating.

The outer end portion of the body (i. e. the end portion remote from the tool-bit holder 23) contains a first race 35 of truncated conical form disposed with its smaller end adjacent to the motor. When the striker is rotating within the smaller end of the race 35, the radial thrust of the rollers 31 causes a reaction which accelerates the striker inwards towards the tool-bit holder. The lower end face of the striker may be convex at 36 to co-operate with a concave annular surface 37 on the tool-bit holder.

Immediately adjacent to the larger end of the first race 35 is a second race 38, the object of which is to impart to the striker, after its impact with the tool-bit holder, an acceleration in the outward direction sufficient to return it to the smaller end of the first race, while causing only a relatively slight retardation of the inward movement of the striker as it passes through the second race towards the end of its in-stroke. With this object in view, the second race is provided with two diametrically opposed helical paths of such a section that in any plane normal to the axis of the motor shaft this race, which will hereinafter be termed the "dynamic screw," everywhere presents a concave surface to the rollers, which is the condition determining continuous contact between the rollers and the dynamic screw.

The preferred cross section of the dynamic screw varies from a circle adjacent to and registering exactly with the larger end of the race 35, through ovals (e. g. Fig. 6), of more or less elliptical form, having the same major axis and minor axes which progressively decrease towards the inner end of the dynamic screw. The major axis of the oval at any section is angularly displaced about the axis of the motor shaft, in the direction opposite to the direction of rotation of this shaft, with respect to the major axis of the oval at any section nearer the outer end of the dynamic screw, so that the hand of the helical paths defined by the parts of successive ovals adjacent to the ends of their major axes is opposite to the

hand of the helixes traced out by the rollers during the in-stroke of the striker.

Fig. 7 represents diagrammatically on a reduced scale a developed view of the inner surface of the dynamic screw. The two helical paths are similar and each is produced by a family of helical grooves the centre lines of which intersect at A and the pitch angles of which range between the limits β_1 and β_2 (which may be for example 7° and 9° respectively), so that the grooved paths become progressively wider towards the outer end of the dynamic screw, while the height of the lands between the grooved paths decreases towards the outer end owing to the merging of these paths into each other. Such a screw can be machined on a screw-cutting lathe having a milling attachment, with the aid of a milling cutter having a suitably profiled periphery and employed to cut in succession the several grooves of the said family forming each path.

At the inner end of the dynamic screw 38 there is preferably a short race 39 the bore of which has an oval section which is the same as the section of the inner end of the dynamic screw 38 but which is not helical. The major axes of these two sections are relatively displaced through a small angle, e. g. 15° as shown in Fig. 8 (where for the sake of clearness the ovals are shown in exaggerated form), while the adjacent edges of the two parts 38 and 39 are rounded, as shown in Figs. 9, 10 and 11. The race 39 is provided with a circumferential groove 40.

The races 35 and 39 and the dynamic screw 38 are locked in the tubular body 20 of the tool by means of an externally screw-threaded ring 41 engaged in the end of the body and bearing against a flanged portion 42 of the inner end cap 24, which in turn bears against the race 39. The races, the dynamic screw and the rollers 31 are hardened and ground to a high surface finish.

The tool-bit holder 23 is associated with a spring 43 compressed between the end of a counterbore 44 in the end cap 24 and a guide ring 45 retained by a snap ring 46 engaged on the tool-bit holder which is thereby resiliently biased towards the position shown.

The operation of the tool will now be described, starting from the condition in which the striker 26 is being rotated at normal speed in the direction of the arrow in Fig. 1 and is within the upper part of the race 35. The rollers 34 rotating with the striker are urged radially outwards by centrifugal force and co-operate with the diverging race 35. The axial components of the forces acting between the race and the rollers accelerate the striker inwards.

When the rollers 31 leave the inner end of the race 35, the momentum of the striker carries it into the dynamic screw. The helixes now described by the rollers are of the opposite hand to the helical paths in the dynamic screw, so that the rollers move more or less transversely to these paths; under these circumstances, since the threads of the screw and the ridged portions 34 of the rollers are of smoothly curved profile, there is only a very loose dynamic coupling between the striker and the screw and the retardation of the inward movement of the striker is relatively slight.

The tool bit being in contact with work, the tool-bit holder will be raised to a position such that its surface 37 is against the inner end of the shaft 25A. Consequently the striker will strike the tool-bit holder while the rollers 31 are engaged in the dynamic screw. When the striker

has spent its axial momentum in the blow upon the tool-bit holder, and even if there is no recoil from the latter, the dynamic coupling between the striker and the screw increases to a value such that the screw is effective in accelerating the striker outwards in readiness for another cycle. This effect will be explained with reference to Figs. 12 and 13. In the development of the screw shown in Fig. 12, line G denotes the bottom of a groove, and line R the top of the dividing ridge on the inner side of this groove. For the sake of simplicity the slope S between the lines G and R will be regarded as having the uniform gradient ϕ (Fig. 13). The roller 31 contacts the dynamic screw at the bottom of the groove at the point A in Fig. 12 and passes onto the slope S. A centrifugal force F urges the roller 31 radially outwards against the slope S, and the axial component $C=F \tan \phi$, of the force acting between the roller and the screw accelerates the striker outwards so that the roller describes a path P. If v_0 is the velocity of whirl of the point of contact between roller and slope S, the final translatory velocity outwards attained at the intersection of lines G and P is $v=v_0 \tan 2\phi$, friction being neglected. It is usually preferable to arrange that the path P shall, as shown, leave the slope S at its outer edge; though in some circumstances the path P may cross the ridge R and enter the next succeeding helical groove.

The translatory velocity so imparted to the striker is sufficient to return it to the race 35, the tapered surface of which constrains the rollers to move inwards against the centrifugal forces acting on them and thus arrests the translatory part of the motion of the striker. Thereafter the rollers, continuing to press upon the conical surface of the race, cooperate with the latter to force the striker out again so that the striker leaves the race 35 with a translatory velocity which, if friction is neglected, will be equal to that with which it entered the race 35. Thus the cycle will repeat automatically.

The race 38 forms a starting and idling zone for the rollers 31, in which the striker can be brought up to normal speed when the motor is switched on and before the tool is set to work. The groove 40 forms a track round which the rollers can run idly. When the tool is set to work after the motor has run up to speed, outward movement of the tool-bit holder 23 as the tool is engaged with the work causes the striker to be displaced outwards until the ridged portions 34 of the rollers engage the sinuous groove formed by the rounded edges of the race 39 and the dynamic screw, as shown in Figs. 9, 10 and 11. This sinuous groove operates to project the striker into the dynamic screw in such a way that the ridged portions of the rollers enter the helical paths at spots so selected that the points of contact between the rollers and the race will follow substantially the ideal path P (Fig. 12).

The frequency of the movement of the striker is controllable by varying its total weight, the weight and profile of the rollers, the dimensions of the race 35 and the pitch and form of the dynamic screw; and this frequency can easily be made a small fraction of the speed of revolution of the motor, which may be as high as 10,000 R. P. M. in a hand tool.

In intermittent service, such as riveting, the motor may be allowed to run continuously, since the power consumption is low while the tool is idling. During idle intervals the motor speed may be allowed to rise, and the energy thereby

stored in the rotary masses is usefully employed in the next working period as the motor speed drops with increasing load. This possibility of energy storage enables a small and light motor to be used. A motor having a drooping torque-speed characteristic, e. g. a series motor, is particularly suitable for this application.

The mechanical parts can be kept well lubricated by splash by introducing a small quantity of oil within the tubular body 20, which is of oil-tight construction.

Figs. 4 and 5 show two alternative forms of striker. In Fig. 4 the rollers 31A are rotatable in hollow rectangular carrier blocks 47 which are slidably guided in pockets 30A in the striker 26A. In Fig. 5 balls 31B are provided instead of rollers and are a working fit in pockets 30B in the striker 26B. Rollers are generally preferable, since their profile can be adapted to design requirements, whereas the radius of balls is fixed by the mass desired.

I claim:

1. A percussion tool including a rotary driving member, a diverging tubular race co-axial with said driving member, a second tubular race adjacent to the larger end of said diverging race and having helical paths on its interior surface, a striker co-axial with and constrained to rotate with said driving member and reciprocable along said axis, said striker having centrifugal masses constrained to rotate with it and capable of co-operating with said helical paths for transforming the kinetic energy of rotation of said striker into striking energy of translation of said striker, and an abutment member capable of arresting such translatory movement of said striker while said striker is within said second race, said helical paths being of opposite hand to the helices traced out by said masses during the translatory movement of said striker towards said abutment member.

2. A percussion tool including a rotary driving shaft, a tubular body, a striker connected for rotation with said shaft and capable of reciprocating longitudinally within said body along the axis of said shaft into engagement with a tool-bit holder slidably mounted in the inner end of said body, said striker having a plurality of centrifugal masses uniformly distributed around it and constrained to rotate and reciprocate with it, but capable of moving at least in part radially with respect to the striker, the interior surface of said body forming near its outer end a race for said masses, which diverges in the inward direction for the purpose of accelerating the striker on its in-stroke, the interior surface of said body forming beyond the inner end of said diverging race a second race providing helical paths for influencing the motion of said masses for the purpose of accelerating the striker on its out stroke, and the hand of said helical paths being opposite to the hand of the helices traced out by said masses during the in-stroke of the striker.

3. A percussion tool including a rotary driving member, a striker co-axial with and constrained to rotate with said driving member and reciprocable along the axis of rotation of said member, a tubular race co-axial with said driving member and having helical paths on its interior surface, said striker comprising centrifugal masses constrained to rotate and reciprocate with it and capable of moving at least in part radially with respect to said axis while co-operating with said interior surface, an abutment member positioned to be struck by said striker at the end

of its stroke in which the hand of the helices traced out by said masses is opposite to the hand of said helical path, and means for reversing the direction of translation of said striker at the other end of its stroke, the shape of said interior surface being such as to impose on said masses when in contact with every point on said surface an acceleration having a component towards said axis, irrespective of the axial velocity of said striker.

4. A percussion tool including a rotary driving member, a striker co-axial with and constrained to rotate with said driving member and reciprocable along the axis of rotation of said member, a tubular race co-axial with said driving member and having helical paths on its interior surface, said striker carrying centrifugal rolling elements constrained to rotate and reciprocate therewith and capable of moving at least in part radially with respect to said axis while rolling round said interior surface, an abutment member positioned to be struck by said striker at the end of its stroke in which the hand of the helices traced out by said masses is opposite to the hand of said helical paths, and means for reversing the direction of translation of said striker at the other end of its stroke, the shape of said interior surface and of said rolling elements being such as to impose on said rolling elements when in contact with every point on said surface an acceleration having a component towards said axis, irrespective of the axial velocity of said striker.

5. A percussion tool including a rotary driving member, a diverging tubular race co-axial with said driving member, a second tubular race adjacent to the larger end of said diverging race and having helical paths on its interior surface, a striker co-axial with and constrained to rotate with said driving member and reciprocable along said axis, said striker having centrifugal rollers constrained to rotate and reciprocate with it while rolling round the interior surfaces of said races, said rollers co-operating with said helical paths for transforming the kinetic energy of rotation of said striker into striking energy of translation of said striker, and an abutment member capable of arresting such translatory movement of said striker while said striker is within said second race, said helical paths being of opposite hand to the helices traced out by said rollers during the stroke of said striker towards said abutment.

6. A percussion tool including a tubular body, an electric motor at one end of and co-axial with said body, a tool-bit holder slidably mounted co-axially with and in the other end of said body, said motor having a shaft extending co-axially within said body, a bearing between the end of said shaft and said tool-bit holder, a striker mounted on and constrained to rotate with said shaft and reciprocable within said body for co-operation with said tool-bit holder, said striker having centrifugal masses constrained to rotate with it and movable at least in part radially with respect to said axis while co-operating with the interior surface of said body, said interior surface having grooved helical paths in the portion thereof that co-operates with said masses when said striker is impacting said tool-bit holder, the hand of said helical paths being opposite to that of the paths traced by said masses while said striker approaches said tool-bit holder, and means for reversing the direction of the translatory motion of said striker while it is in the neighborhood

of the end of said body adjacent to said motor and thereby returning said striker into said grooved portion.

7. A percussion tool including a tubular body, an electric motor at one end of and co-axial with said body, a tool-bit holder slidably mounted co-axially with and in the other end of said body, said motor having a shaft extending co-axially within said body, a bearing between the end of said shaft and said tool-bit holder, and a striker mounted on and constrained to rotate with said shaft and reciprocable within said body for co-operation with said tool-bit holder, said striker having centrifugal rolling elements constrained to rotate with it and movable at least in part radially with respect to said axis while co-operating with the interior surface of said body, said interior surface diverging from the end nearer to said motor and merging into a portion having grooved helical paths so disposed as to co-operate with said rolling elements when said striker is impacting said tool-bit holder, the hand of said helical paths being opposite to that of the paths traced by said rolling elements while said striker approaches said tool-bit holder.

8. A percussion tool including a tubular body, a rotary driving member, a striker in said body co-axial with and constrained to rotate with said driving member and reciprocable along the axis of rotation of said member, said striker comprising centrifugal masses constrained to rotate and reciprocate with it but movable at least in part radially with respect to said axis, an abutment member slidably carried in said body co-axially with said striker for co-operation with said striker, the interior surface of said body providing an idling track for said masses when said striker is in contact with said abutment member and when said abutment member is extended, and said interior surface also having shallow helical grooves on the side of said idling track remote from said striker for co-operation with said masses so as to accelerate said striker in the direction away from said abutment member, and means in said body co-operating with said striker to reverse the direction of its translatory motion when said striker is remote from said abutment member.

9. A percussion tool including a tubular body, a rotary driving member, a striker in said body co-axial with and constrained to rotate with said driving member and reciprocable along the axis of rotation of said member, said striker comprising centrifugal masses constrained to rotate and reciprocate with it but movable at least in part radially with respect to said axis, an abutment member slidably carried in said body co-axially with said striker for co-operation with said striker, the interior surface of said body having firstly an idling track for said masses when said striker is in contact with said abutment member and when said abutment member is extended, secondly shallow helical grooves on the side of said idling track remote from said striker for co-operation with said masses so as to accelerate said striker in the direction away from said abutment member and thirdly a sinuous circumferential groove between said helical grooves and said idling track and placed to receive said masses on retraction of said abutment member, and means in said body co-operating with said striker to reverse the direction of its translatory motion when said striker is remote from said abutment member.

10. A percussion tool including a rotary driving

member, a striker co-axial with and constrained to rotate with said driving member and reciprocable along the axis of rotation of said member, a tubular race co-axial with said driving member and having helical paths on its interior surface, said striker comprising centrifugal masses constrained to rotate and reciprocate with it and capable of moving at least in part radially with respect to said axis while co-operating with said interior surface, an abutment member for co-operation with said striker while it is in a position such that said masses are traversing said helical paths, and means for reversing the direction of translatory motion of said striker while it is remote from said abutment member, the shape of said interior surface being such that cross sections thereof taken in succession in the direction towards said abutment member are ovals of approximately elliptical form, of which the ratio of major axis to minor axis increases in said direction, while the major axis of the oval at any section is angularly displaced about said axis, in the direction opposite to the direction of rotation of said driving member, with respect to the major axis of the oval at any section more remote from said abutment member.

11. A percussion tool including a tubular body, a driving shaft substantially co-axial with said body, a centrifugal mass constrained to rotate with said shaft but movable parallel and radially with respect to the axis of said shaft, said body having on its interior surface a helical groove with which said mass co-operates under the influence of centrifugal force to produce an axial thrust, means on said body for taking the momentum of said mass in one axial direction and means for reversing the direction of translatory motion of said mass after its displacement in the other axial direction, the shapes of said mass and said groove being such that the dynamic coupling between them is higher when the helical path of the mass is of the same hand as said helical groove than when the helical path of the mass is of the opposite hand to the helical groove.

12. A percussion tool including a tubular body, a driving shaft substantially co-axial with said body, a centrifugal mass constrained to rotate with said shaft but movable parallel and radially with respect to the axis of said shaft, said body having on its interior surface a helical groove with which said mass co-operates under the influence of centrifugal force to produce an axial thrust, and a frusto-conical portion having its larger end adjacent to said groove, the shapes of said mass and said groove being such that the dynamic coupling between them is higher when the helical path of the mass is of the same hand as said helical groove than when the helical path of the mass is of the opposite hand to the helical groove, and such higher dynamic coupling producing on said mass a thrust in the axial direction opposite to that produced on said mass by said frusto-conical portion.

13. A percussion tool including a tubular body, a driving shaft substantially co-axial with said body, a centrifugal mass constrained to rotate with said shaft but movable parallel and radially with respect to the axis of said shaft, said body having on its interior surface a helical groove with which said mass co-operates under the influence of centrifugal force to produce an axial thrust, a frusto-conical portion having its larger end adjacent to said groove, and a cylindrical portion on the side of said groove remote from said frusto-conical portion, the shapes of

said mass and said groove being such that the dynamic coupling between them is higher when the helical path of the mass is of the same hand as said helical groove than when the helical path of the mass is of the opposite hand to the helical groove, and such higher dynamic coupling producing on said mass a thrust in the axial direction opposite to that produced on said mass by said frusto-conical portion.

14. In a percussion tool, a tubular body, a rotatable striker within said body and capable of translation along the axis thereof a motor drivably connected to said striker, said striker in-

cluding a centrifugal mass constrained to follow the rotation and translation of said striker and capable of bearing under the influence of centrifugal force on the interior surface of said body, at least part of said surface having a helical form such as to cause a screwing effect by which part of the rotary motion of said striker is converted into translatory motion in an axial direction, and means for reversing the said translatory motion of the striker, so that under the alternating effects of said helical surface and said reversing means said striker will reciprocate continuously.

RUDOLF GOLDSCHMIDT.
